UNITED STATES PATENT OFFICE

ROBERT J. COPELAND, OF TORONTO, ONTARIO, CANADA

HOLDER FOR LOOSE-LEAF BINDERS

Application filed October 1, 1927. Serial No. 223,434.

The principal objects of the invention are to overcome the difficulties and inconveniences met with in the handling of loose leaf binders, particularly in machine posting, and to facilitate the handling of binders of the shift type in which the sections of the binder back are manipulated to alter the relationship of the prongs on the different sections.

A further important object is to provide a means for supporting the book so that the leaves will lie out perfectly flat, no matter what portion of the book is being used and which also will afford means for an arm rest in making entries on the lower end of the pages.

The principal feature of the invention consists in providing a supporting member for the binder covers and leaves having a recessed portion adapted to receive the sections of the hinged binder back and further, to provide a positive guiding element in said recess to effect the desired positioning of the binder backs.

In the drawing, Figure 1 is a perspective view of a loose leaf binder shown supported by my improved device.

Figure 2 is an enlarged perspective detail of the binder back and the central supporting portion of the holder.

Figure 3 is a perspective view similar to Figure 2 showing the shift binder back moved in shifting the prongs.

Figure 4 is an end elevational view on a reduced scale showing the position of the binder back and support with the binder prongs separated.

Figure 5 is a perspective view of the holder showing one of the arm supports extended.

Loose leaf binders, as at present constructed, are formed with metal binder backs which are hinged centrally of their width and are adapted to swing open to separate the prongs so that the loose sheets may be removed and replaced, but when the leaves are to be turned over the prongs have to be moved to an overlapping position. These conditions require a considerable amount of manipulation and the books are very heavy, consequently much inconvenience is experienced. Further, when the hinge back is

locked with the prongs overlapping the pages will not lie flat.

Also in the type of binder known as a "shift binder" it is very difficult to hold the sheets at one side while a shift is being made and the sheets frequently slip off the prongs causing great inconvenience and loss of time.

The present invention has been devised to overcome the above recited objections and to further assist in the handling of the book and it comprises a holder on which the book is laid.

The holder as here shown is formed of a stiff "board" 1 which may be of metal, fibre, wood or heavy card having a pair of ribs 2 arranged at the ends and a pair of ribs 3 arranged adjacent to the centre. The ribs 3 are preferably bevelled on their inner sides and a rib 4, preferably bevelled on both sides is arranged centrally between the ribs 3.

The ribs 2 and 3 are preferably formed with longitudinal grooves 5 in their inner and outer sides respectively and "boards" 6 having edge ribs 7 are slidably supported in the grooves.

The top surfaces of the boards 6 are preferably arranged flush with the tops of the ribs and the spaces 8 beneath the sliding boards form convenient pockets for holding spare sheets for the books used thereon.

The holder thus described is placed upon a desk and the "binder" 8' is placed thereon as shown in Figure 1. The hinged back is unlocked and the hinge sections rest in the parallel bevelled grooves formed between the centre rib 4 and the adjacent ribs 3, as illustrated in Figures 1 and 2. When the binder is thus placed the points 9 of the binder prongs 10 are not separated so that the sheets 11 may be removed but the binder covers 12 and the sheets 11 rest perfectly flat so that entries may be made with the greatest ease. The sliding "boards" 6 may be drawn out, as shown, to form arm rests. It will be readily seen that as the points of the binder prongs are not separated to allow the sheets to come off such sheets may be turned as effectively as if the binder back were locked.

If it be desired to remove sheets from the binder for machine posting or other reasons

the back sections may be raised, as illustrated in Figure 4, by simply pressing same upwardly with the fingers until the points of the prongs 10 are separated and the prongs will 5 remain separated without holding.

This arrangement relieves the person using the book from holding the heavy book and enables the greatest freedom of operation.

When binders of the shift type are used 10 the book is laid upon the holder and the back is unlocked and the sections then drop into the central grooves with the prongs overlapping, as shown in Figure 2 of the drawing, the centre rib 4 acting to break the hinge 15 joint. The sheets may be turned as desired and when a shift is desired it is merely necessary to slip either half of the binder, with the sheets arranged thereon, lengthwise of the grooves. This can be accomplished with the 20 greatest freedom and both hands can be used in making the shift without the operator having to support or hold the binder or sheets and there will be no possibility of the sheets slipping off the prongs and becoming pied.

25 I have shown a very simple form of construction of holder but it must be understood that the construction may be varied considerably so long as the holder is provided with a recess to allow the hinged back to open and 30 swing below the plane of the underside of the covers.

What I claim as my invention is:

25 1. A holder for loose leaf binders of the curved prong type having a pair of hinged back sections hinged to the covers, comprising a flat board, transverse ribs arranged at the ends of said board, and a pair of transverse ribs arranged adjacent to the centre and forming a central transverse channel recess to receive and position the hinge sections of the binder back, the upper surfaces of all of said ribs being arranged in a common plane and forming rests adapted to engage and support the covers of the binder in a common plane.

40 45 2. A holder for loose leaf binders of the curved prong type having a pair of hinged back sections hinged to the covers, comprising a flat board, transverse ribs arranged at the ends of said board, and a pair of transverse ribs arranged adjacent to the centre and being bevelled on their opposing sides to form a central transverse channel recess of angular cross section to receive and position the hinge sections of the binder back, all of said ribs 55 having upper flat surfaces arranged in a common plane to engage and support the covers of the binder in a common plane.

60 65 3. A holder for loose leaf binders of the curved prong type having a pair of hinged back sections hinged to the covers, comprising substantially horizontal supports for the binder covers adapted to support the covers each in a substantially horizontal position to facilitate entries, said supports being separated by a recess, the walls of said recess be-

ing adapted to co-operatively engage and position the hinged sections in a predetermined angular relation relative to the horizontally supported covers to effect the positioning of the opposing sets of prongs with 70 their ends overlapping, said supports engaging the covers on their outward sides in an extended manner to support the weight of the covers and sheets independent of the back members whereby the latter will be freely 75 suspended within said recess for free manipulation therein.

4. A holder for loose leaf binders of the curved prong type having a pair of hinged back sections hinged to the covers, comprising a rigid member having a pair of flat surfaces disposed in a common plane adapted to support the covers in their open position and a recess extending centrally there-across to allow the hinged back sections to be depressed below the level of the binder covers, the walls of said recess being adapted to engage and position said hinged back sections to support the prongs thereof in predetermined relation, said supports engaging the covers on their outward sides in an extended manner to support the weight of the covers and sheets independent of the back members whereby the latter will be freely suspended within said recess for free manipulation 95 therein.

5. A holder for loose leaf binders of the curved prong type having a pair of hinged back sections hinged to the covers, comprising a board adapted to support the covers of said binder in an open position, in a common horizontal plane said board having a bevelled recess extending thereacross adapted to receive and engage said hinged back sections when depressed to support the same in a predetermined angular relation to the horizontally supported covers, said boards engaging the covers on their outward sides in an extended manner to support the weight of the covers and sheets independent of the back members whereby the latter will be freely suspended within said recess for free manipulation 105 therein.

6. A holder for loose leaf binders of the curved prong type having a pair of hinged back sections hinged to the cover, comprising a flat board having a bevelled recess extending across its flat surface intermediate of its length adapted to receive and position the back hinged section when depressed, said board supporting the cover members at either side of said recess in a substantially common plane, and supporting the weight of the covers and sheets independent of the back members whereby the latter will be suspended within said recess for free relative movement in positioning the prongs, and a bevelled rib arranged centrally in said recess adapted to co-operate with the hinged sections of the binder back.

7. A holder for loose leaf binders of the curved prong type having a pair of hinged back sections hinged to the covers, comprising a plurality of supports separated by a central recess for adjustably receiving the hinged back sections, said supports presenting substantially horizontally related cover-contacting areas adjacent to and at points spaced from said central recess at each side thereof
- 5 to support said covers positively in a substantially horizontal plane to facilitate entries and effect the suspension of the back sections for free movement in said recess to facilitate the manipulation of the prongs,
- 10 15 said recess having walls adapted to engage and position each of the hinged back sections of the cover in a predetermined angular relation to the other and to its respective horizontally supported cover.
